UNITED STATES PATENT OFFICE.

LOUIS HOFFMAN, OF SAN FRANCISCO, CALIFORNIA.

SHIP.

Specification of Letters Patent. Patented Nov. 19, 1918.

1,285,182.

Application filed March 25, 1918. Serial No. 224,580.

To all whom it may concern:

Be it known that I, LOUIS HOFFMAN, a citizen of Russia, residing at San Francisco, in the county of San Francisco and State of California, have invented certain new and useful Improvements in Ships; and I do declare the following to be a full, clear, and exact description of the invention, such as will enable others skilled in the art to which it appertains to make and use the same.

My invention has for its object to provide an ocean-going vessel which will be practically immune from torpedo attack, the ship being constructed of upper and lower hull sections spaced apart sufficiently to permit an approaching torpedo to pass between the two without injuring the vessel, provision being made however for localizing the injury as much as possible in case the torpedo should strike and explode.

With the foregoing in view, the invention resides in the novel features of construction and unique combinations of parts to be hereinafter fully described and claimed, the descriptive matter being supplemented by the accompanying drawings which form a part of this specification and in which:

Figure 1 is a side elevation of the improved ship;

Fig. 2 is a central vertical longitudinal section;

Fig. 3 is a horizontal section on the plane of the line 3—3 of Fig. 2; and

Figs. 4 and 5 are vertical transverse sections on the planes of the lines 4—4 and 5—5 respectively of Fig. 2.

In the drawings above briefly described, the numeral 1 designates an upper hull section floating substantially on the surface of the water, while the numeral 2 designates a lower submerged hull spaced below the hull section 1 sufficiently to permit torpedoes to pass between the two, the front and rear ends of the two hull sections however being joined to provide a prow 3 and stern 4 of usual construction, so that as little resistance as possible is offered to the progress of the ship, said prow and stern being honey-combed with air tight compartments 5, whereby even though one part of said stern or prow be injured, the remainder thereof will not be flooded.

Extending vertically between the two hull sections 1 and 2 and securing them together, are longitudinally spaced struts 6, the inner edges of said struts being preferably of

semi-cylindrical formation as seen at 7 while the outer edges thereof are beveled to substantial knife edges as shown at 8 to provide torpedo deflecting means. Furthermore, to provide additional deflecting means, the bottom 9 of the upper hull section 1 is inclined upwardly at its edges as shown in Figs. 4 and 5 and the top 10 of the lower hull section 2 inclines downwardly at 65 its edges as also seen in the figures referred to. By the arrangement of parts described, a plurality of torpedo passages P are provided through the ship and the inclines of the parts 9 and 10 together with the bevels 8 of the struts 6, form flared ends for guiding the torpedoes through said passages, it being intended that they shall pass freely through without in any manner injuring the vessel. Even should one or more of the struts 6 be damaged, however, water will not be admitted into either the upper or the lower hull section, since the ends of said struts are closed against communication with said hull sections as shown clearly in Fig. 4. 80 Also, each strut is preferably divided into a pair of compartments by a vertical partition 12, so that injury to one part of the strut need not affect the other.

The upper hull section 1 will be used principally for carrying the passengers, while the machinery of the ship and any cargo will be stowed in the lower hull section 2, the two hulls being in communication by means of preferably cylindrical vertical passage members 13 and 14, said passage members 13 having suitable doors or hatchways 15 opening into the hulls 1 and 2, while the passage members 14 in addition to being provided with hatchways or doors, open onto the upper deck of the vessel. Suitable stairways, elevators or the like may be provided in the passage members 13 and 14 but for illustrative purposes need not be shown. In all cases however these passage members are 95 preferably located between certain of the struts 6 as shown in Fig. 3, so that said struts will guard said passage members against torpedoes.

The interior construction of the hull sections 1 and 2 will vary according to the uses of the ship, but in most cases the section 1 will be provided with a horizontal floor 16, while a central compartment 17 will extend longitudinally through the lower section 2, 110 whereby to provide air tight compartments 18 along the edges of said last-named section

and similar compartments 19 and 20 above and below said compartment 17, this provision being preferable in order that injury to one part of the hull section 2 and flooding thereof with water need not affect the remainder thereof. The compartments 18 and 20 may be used for carrying cargo if desired, in which case it would be necessary to provide suitable bulk heads 21 to cut off 10 communication with the central compartment 17 whenever necessary (see Fig. 4).

From the foregoing, taken in connection with the accompanying drawings, it will be obvious that although my invention is of 15 rather simple nature, it will be practically invulnerable to torpedo attack. Even though certain parts of the ship be injured, the remainder thereof will be unaffected and will remain in a seaworthy condition. Due to 20 these advantages, the improved vessel is particularly well adapted for use as a transport or passenger vessel, but equally well applicable as a freighter.

Since probably the best results are obtained from the several details shown and described, these details are preferably em-

ployed, but within the scope of the invention as claimed, numerous minor changes may well be made.

I claim:

In a torpedo resisting ship, a hull partly below and partly above the water line, said hull having throughout the greater part of its length a longitudinal torpedo passage which opens through the sides of the hull at a distance below the water level equal to the traveling depth of a torpedo, the top, 30 bottom and ends of the passage being beveled to direct torpedoes into said passage, the stern and prow of the hull between the 35 ends of said passage and the extreme ends of said hull being free from openings below the water level and being honey-combed with air-tight compartments.

In testimony whereof I have hereunto set 40 my hand in the presence of two subscribing witnesses:

LOUIS HOFFMAN.

Witnesses:

BENJMAN LEKTMAN,
B. H. RIVISE.
